DESIGN FOR A LIGHTING FIXTURE HEAD OR SIMILAR ARTICLE

Frederick Max Poritz, New York, N. Y., assignor to Artistic Brass & Bronz Works, Inc., New York, N. Y., a corporation of New York

Application September 28, 1933. Serial No. 49,362

Term of patent 7 years

To all whom it may concern:

Be it known that I, FREDERICK MAX PORITZ, a German citizen, and a resident of the borough of Manhattan, city, county, and State of New York, have invented a new, original, and ornamental Design for a Lighting Fixture Head or Similar Article, of which the following is a specification, reference being had to the accompanying drawing forming a part thereof.

The figure is an elevation of a lighting fixture head, showing my new design.

I claim:

The ornamental design for a lighting fixture head or similar article, as shown.

FREDERICK MAX PORITZ.
